Inventor
Charles Meister
By his Atty.

UNITED STATES PATENT OFFICE.

CHARLES MEISTER, OF PHILADELPHIA, PENNSYLVANIA, ASSIGNOR TO
FREDERICK J. ANSPACH, OF SAME PLACE.

TREMOLO FOR CORNETS.

SPECIFICATION forming part of Letters Patent No. 377,493, dated February 7, 1888.

Application filed March 1, 1886. Serial No. 193,546. (No model.)

To all whom it may concern:

Be it known that I, CHARLES MEISTER, of the city and county of Philadelphia and State of Pennsylvania, have invented an Improvement in Mouth-Pieces for Cornets, of which the following is a specification.

My invention has reference to musical instruments, particularly relating to cornets; and it consists in certain improvements, fully set forth in the following specification, and shown in the accompanying drawings, which form part thereof.

When what is known as "double" or "triple" tonguing is produced, a most wonderful and pleasing effect is given to solo-playing. With amateurs this effect is one which offers great difficulties and is attainable only by constant and most wearying practice, in many instances covering a period of several years.

The object of this invention is to produce this effect by a mechanical attachment readily applied to all cornets or equivalent instruments. The use of this attachment will enable a performer to produce double and triple tonguing notes and also a tremolo, and the said effects may be produced instantaneously by a simple movement of one of the fingers, preferably of the left hand. In addition to the above effects it is well known that to play the notes in the high registers or above the staff the mouth must be contracted and rigidly held with a smaller opening. This change of the mouth and the necessarily increased air-pressure is a source of more or less discomfort to the player where long and constant and high-register playing is required; and, further, the object of my improvement is to overcome this difficulty by a mechanical attachment which shall be capable of changing the larger orifice in the mouth-piece to one of smaller diameter, thus accomplishing in a mechanical way what has heretofore been necessarily produced by the lips or changing of the mouth-piece.

The essential feature of my invention consists in providing the mouth-piece with a valve attachment capable of being reciprocated by the action of the fingers to intermittently cut off the passage of air, and thus in effect produce pulsations. The rapidity of these pulsations

will produce a varied effect, as desired. A single reciprocation of the valve in one direction may be caused to open in succession two or more ports or passages, and, if desired, these passages may be all of one diameter or of different diameters.

In the drawings, Figure 1 is a side elevation of a cornet embodying my improvements, showing the mouth-piece in section; and Fig. 2 is a sectional elevation of a modified arrangement of mouth-piece, showing the orifice in the valve, two or more in number and of different diameters.

A is the mouth-piece, and B is the extension-tube, which may be of any length or shape as is customary in cornets or instruments of this class. The bulb D of the mouth-piece is provided with a vertical valve-passage, E, which crosses the air-passage d.

F is the valve, and works in the passage E, and is preferably limited in its upward and downward movement by shoulders f.

G are pads or mufflers to prevent a sound during the striking of the valve at the limits of its movements. This valve is provided with one or more openings or orifices, H, arranged parallel to the air-passages d, whereby as the valve is reciprocated the current of air may be intermittently cut off and continued, forming pulsations.

The valve F may be reciprocated directly by pressing the finger upon it substantially in the manner of the main piston-valves C, or it may be reciprocated by a connection passing to the forward part of the instrument, where the first or second finger of the left hand may operate it. This last arrangement is shown in the drawings. The mouth-piece is provided with a standard, K, to which is pivoted the lever J, one end of which is connected to the valve F at I.

T is a spring operating on the said lever to cause the valve to be raised, as shown in Fig. 1. This lever J is oscillated by the rod L being reciprocated through its support or bearing N, which is adjustably clamped at O to the extension-section B of the cornet.

M M' are two stops secured to the rod L and arranged on each side of the support to

limit the reciprocation of the said rod. The pads *m* prevent the said stops from striking directly against the support, and thereby muffle the sound.

5 R is a finger-piece connected by a shank, *r*, with the adjustable tubular section *s*, fitted to the end of the rod *L*, and secured thereon by a set-screw, *S*. The length of this rod and finger-piece may be varied to suit different 10 sizes of cornets and different lengths of extension-sections by simply loosening the set-screw *S*, adjusting the thumb-piece longitudinally upon the rod *L*, and fastening it in such new position.

15 P is a guide-rod secured to one of the stops of the piece *M*, and works through a guide, *p*, on the support *N*; but any other form of guide device may be used. As shown, a pressure upon the finger-piece *R* would cause 20 each of the openings or orifices *H* in the valve to pass successively before the opening *d*, thereby with each reciprocation of the valve making a series of pulsations or intermittent puffs of air equivalent in its effect to what is 25 produced in double and triple tonguing. By a very rapid action of the valve between two passages *H* a tremolo effect may be produced.

Referring to Fig. 2, it will be observed that the valve is shown as provided with two orifices, the upper of which is of smaller diameter than the lower one. If the upper hole, *h*, be brought in line with the air-passage *d*, the same action of the mouth which, with the large opening *H*, produces the lower tones 35 will now produce the high notes. If this valve be reciprocated rapidly, as previously described, the peculiar tonguing effect will be produced, as hereinbefore specified.

I do not limit myself to any particular form 40 or shape of valve or the means for accomplishing the reciprocations, as they may be changed or modified to suit the ideas of the manufacturer and the instrument to which it is to be applied. Neither do I limit myself to 45 the number of orifices in the valve or the sizes of same.

Having now described my invention, what I claim as new, and desire to secure by Letters Patent, is—

50 1. A mouth-piece for a cornet or equivalent wind-instrument, provided with a valve to interrupt the current of air and produce pulsations, in combination with a key to reciprocate said valve, whereby the effects of double and triple tonguing and tremolo may be mechanically obtained, substantially as and for the purpose specified.

55 2. A mouth-piece for a cornet or equivalent wind-instrument, provided with a valve having a series of orifices or apertures to interrupt the current of air and produce pulsations, in combination with a key to reciprocate said valve, whereby the effects of double and triple tonguing and tremolo may be mechanically obtained, substantially as and for the purpose specified.

3. A mouth-piece for a cornet or equivalent wind-instrument, provided with a valve having two or more orifices or apertures of different sizes or areas to interrupt the current of 70 air and produce pulsations, in combination with a key to reciprocate said valve, whereby the effect of double and triple tonguing and tremolo may be mechanically obtained, substantially as and for the purpose specified. 75

4. A mouth-piece for a cornet or equivalent wind-instrument, provided with a valve to interrupt the current of air and produce pulsations, whereby the effects of double and triple tonguing and tremolo may be mechanically obtained, in combination with a finger piece or key to reciprocate said valve, substantially as and for the purpose specified. 80

5. A mouth-piece for a cornet or equivalent wind-instrument, provided with a valve to interrupt the current of air and produce pulsations, whereby the effects of double and triple tonguing and tremolo may be mechanically obtained, in combination with the body portion 85 of the cornet and a finger piece or key to reciprocate said valve, having an extension whereby it is brought to the forward part of the cornet, substantially as and for the purpose specified. 90

6. A mouth-piece for a cornet or equivalent 95 wind-instrument, provided with a valve to interrupt the current of air and produce pulsations, whereby the effects of double and triple tonguing and tremolo may be mechanically obtained, in combination with the body portion 100 of the cornet and a finger piece or key to reciprocate said valve, having an adjustable extension whereby it is brought to the forward part of the cornet, substantially as and for the purpose specified. 105

7. A cornet having the usual tone-valves and 110 provided with an auxiliary wind-interrupter in the mouth-piece to admit the air to the valves in pulsations, substantially as and for the purpose specified. 110

8. A cornet having its mouth-piece provided with a loose valve mechanism for changing the area of the wind-passage and a key to rapidly reciprocate said valve, substantially as and for the purpose specified. 115

9. The cornet-body, in combination with the extension-section *B*, the mouth-piece *A*, having a reciprocating valve, a support, *K*, removably clamped to the cornet, and a reciprocating rod working in said guide to operate the valve 120 and provided on its end with a finger-piece, substantially as and for the purpose specified.

10. The cornet-body, in combination with the extension-section *B*, the mouth-piece *A*, having a reciprocating valve, a support, *K*, 125 removably clamped to the cornet, a reciprocating rod working in said guide to operate the valve and provided on its end with a finger-piece, and stops upon said rod to limit its movement in either direction, substantially as 130 and for the purpose specified.

11. The cornet-body, in combination with

the extension-section B, the mouth-piece A, having a reciprocating valve, a support, K, removably clamped to the cornet, and a reciprocating rod adjustable as to its length and working in said guide to operate the valve and provided on its end with a finger-piece, substantially as and for the purpose specified.

12. The combination of the cornet mouth-piece A, having the valve F, lever T, to move

said valve in one direction, and a spring to move said valve in the other direction, substantially as and for the purpose specified.

In testimony of which invention I hereunto set my hand.

CHARLES MEISTER.
